PATENTED JUNE 19, 1906.

R. TRUSWELL.
MOLD FOR CASTING ANODE PLATES.
APPLICATION FILED OCT. 9, 1905.

UNITED STATES PATENT OFFICE.

RICHARD TRUSWELL, OF TRAIL, CANADA.

MOLD FOR CASTING ANODE-PLATES.

No. 823,977.

Specification of Letters Patent.

Patented June 19, 1906.

Application filed October 9, 1905. Serial No. 281,950.

To all whom it may concern:

Be it known that I, RICHARD TRUSWELL, a citizen of the Dominion of Canada, residing at the town of Trail, in the Province of British Columbia, Canada, have invented a new and useful Improvement in Molds for Casting Anode-Plates, of which the following is a specification.

My invention relates to an improved mold for the casting of anode-plates such as are used in the electrolytic refining of metals, and is designed to provide plates of more uniform thickness, free from warp or twist, and of greater soundness, in their freedom from dross or sponginess, than such as are made under the present practice. In the present practice these plates are usually cast on the horizontal in shallow flat open molds and are in consequence considerably warped and twisted and require to be hammered flat before use. Otherwise with the limited clearance between the plates in the trough the adjacent plates might contact. Being cast in open molds and without head of fluid metal the plates are also of irregular thickness and subject to flaws, which as the plates become reduced in thickness cause portions to break away, and these broken portions lie on the bottom of the trough and may contact with adjoining plates and short-circuit the current, causing not only loss of power, but involving the loss of time and labor in removing broken plates from the trough which have not been fully used up. I have therefore designed a mold in which the plates can be cast on end with the upper part or head of the plate downward, thus insuring a sound flat plate of uniform thickness and free from flaws, particularly in the upper part. I further so construct the mold and support it on trunnions on a truck or car that after casting it may be run out to the tank-room, the mold inverted, and the portion inclosing the head opened, when the plate may be withdrawn from the mold in a condition ready for immediate use.

The particular construction and operation of the mold are fully set forth in the following specification and illustrated in the drawings which accompany it.

Figures 1 and 2 are profile views of the plates for which the construction of the mold is particularly adapted; Fig. 3, a front elevation of the mold mounted as for pouring; Fig. 4, a cross-section of the same on the line A A in Fig. 3; Fig. 5, an end elevation of the

mold inverted after casting and with the mold opened for removal of the cast plate; Fig. 6, a detail cross-section of the slide and nut of the opening portion of the mold; Fig. 7, a detail section showing a modification of the form of joint between the head and plate portion of the mold by which the parts which inclose the head are sustained when inverted to the body of the mold.

In the drawings the anode-plate is represented by 2, that shown in Fig. 1 being provided with laterally-projecting horns 3, by which the plate is supported on the walls of the trough, and that shown in Fig. 2 having eyes 4, which are usually bent and cast into the plate, but which in my mold may be cast with the plate. These parts render the draw-back necessary, which will be later described, and it must be understood that, although the mold is illustrated as made for the form of plate illustrated in Fig. 1, the same construction of parts is equally applicable to that illustrated in Fig. 2 or to any modification in the form of the head.

The main body or plate portion of the mold is formed of two recessed parts 5, secured together by any suitable fastening, such as bolts or rivets, so that the recesses when together will leave a space 6 to form the mold of the lower or uniform portion of the plate, and these recesses are carried to the end of the mold, so that the metal may be poured from that end, which forms the lower end of the plate when in position in the trough. The head of the plate, including the horns 3 or eyes 4, as the case may be, is formed by two portions 7, each having recesses 8 to form the desired width and shape of head, which they entirely inclose, and these portions 7 are slideable outward from the middle plane of the mold a sufficient distance to clear the mold from the projecting portions of the plate which has been cast within it. The contiguous edges of 7 on 5 are beveled, as at 9, so that they will form a close joint when together, while they may be drawn freely back.

Each draw-back portion 7 is furnished at each side with outwardly-projecting members 9, by which they are slidably supported on V-shaped slides 10 on brackets 11, projecting from the sides of 5 adjacent, and the parts 7 are slideable to or from the plane of division by screws 12, having right and left hand threads on their opposite ends, which, respectively, pass through corresponding nuts 13, secured by screws to the parts 7.

These screws 12 are supported in bearings 14, upwardly projecting from the outer ends of the brackets 11, and are rotatable therein by a hand-wheel 17 on either one or the other, 5 while a shaft 15, extended between the two screws and connected to them by bevel-pinnions 16, enables them to be simultaneously operated.

The mold is pivotally mounted by trunnions 20, secured to or forming a part of the plate portion 5 in a frame 21, provided with wheels, and is furnished with a hand-wheel 22, by which it may be inverted in the frame.

In the operation of the device the parts 7 10 are tightly closed through the operation of the right and left hand screws 12, and the mold is inverted to bring the open end of it uppermost, as in Figs. 3 and 4. The metal is then poured in, and the mold may be run 15 on its carriage into the tank-room, and when the metal is set the mold is again inverted, the parts 7 withdrawn, as represented in Fig. 5, 20 when the plate may be drawn from the mold. A slight amount of draw may be desirable in 25 the width and thickness of the plate toward the open or pouring end of the mold to facilitate removal of the plate from the head end.

It may be found necessary to directly support the head end members 7 to the main 30 body or plate members 5 when the head-mold is closed to enable them to sustain their weight and that of the fluid metal within the mold, for which purpose some such modification as is shown in Fig. 7 may be adopted, 35 wherein a joggle or engaging lips 18 are provided on the contiguous edges of 5 and 7. These engaging lips will secure these parts of the mold against movement apart endwise.

With this device the plate being cast in an 40 inclosed mold will be of uniform thickness and not liable to be warped and twisted, and being cast on end and under a head of fluid metal it will be sound and free from sponginess and dross, which will rise toward the 45 gate or place of pouring, and being at the lower end of the plate when in place in the trough its defects will be less injurious.

Having now particularly described the construction and operation of my invention, 50 I hereby declare that what I claim as new, and desire to be protected in by Letters Patent, is—

1. In a mold of the class described; the combination with a portion composed of two

recessed pieces secured together to form a 55 mold to cast that portion of the plate having a uniform width and thickness, of two laterally and oppositely movable members contiguous thereto and recessed that when together they will form a mold to complete the 60 irregularly-formed head portion of the plate, means for forming a close joint between the plate-forming and head-forming portions of the mold, brackets outwardly projecting from the plate-forming portion having V- 65 guides on which corresponding V-shaped guides of the head-forming portions are oppositely slidable, bearings at the ends of the brackets in which are rotatable screws having right and left hand threads at the opposite 70 ends, nuts corresponding to the screw-threads which nuts are removably secured to the head-forming portions of the mold, means for simultaneously rotating the screws to advance and retire the head-forming portions, 75 trunnions for sustaining the mold in a frame or carriage provided with wheels, means for reversing the position of the mold on the trunnions, and a gate through which metal 80 may be poured into the mold.

2. In a mold of the class described, the combination of a main body portion having a chamber to form the main portion of the plate, a head portion forming a continuation of the main body portion, and separable 85 therefrom, said head portion comprising a pair of sections engaging one another, a plurality of reversely-threaded screws passing through said head-sections for moving said head-sections toward or from each other and 90 toward or from the central vertical plane of the mold, means for simultaneously operating all of said reversely-threaded screws to move the head-sections toward or from each other while maintaining their parallel relation, a carriage in which said mold is mounted and means for turning the mold on a horizontal axis to invert the same, said head-sections having a tongue-and-groove connection 95 with the main body portion of the mold, substantially as shown and described.

In testimony whereof I have signed my name to this specification in the presence of two subscribing witnesses.

R. TRUSWELL.
